of this rod are bent
loop 11 at the inner
which loop extends 110

To all whom it may concern:

Be it known that I, INA D. KINNE, a citizen of the United States, residing at Portland, in the county of Multnomah and State of Oregon, have invented certain new and useful Improvements in Pan-Scraping Devices; and I do declare the following to be a full, clear, and exact description of the invention, such as will enable others skilled in the art to which it appertains to make and use the same.

This invention relates to kitchen utensils and more particularly to scraping devices for kettles, pans and the like.

15 The object of the invention is to so construct a device of this character that it may be used to perform the double function of a cleaning device and also as a device for preventing sticking of the food while cooking 20 without necessitating stirring of the food throughout the body portion thereof.

Another object is to provide a device of this character which may be readily and effectively used for scraping and cleaning 25 not only flat but rounded surfaces and which will readily adjust itself to the position for reception of the hand of the user required to reach any desired portion of the surface of a utensil.

30 Another object is to provide peculiar means for connecting the handle of the scraping device therewith whereby said handle will be held at an angle in relation to the scraping element when in its extreme lowered position so that the disk may be used 35 in a tilted position to increase its scraping capacity and effectiveness.

With these and other objects in view the invention consists of certain novel features 40 of construction and the combination and arrangement of parts hereinafter described and claimed.

In the accompanying drawings: Figure 1 represents a perspective view of this improved device; Fig. 2 is a bottom plan view thereof; Fig. 3 is a transverse section taken on the line 3—3 of Fig. 2 with the handle of the device shown upright in full lines and in partially lowered position in dotted lines, 50 the dotted line positions showing the position assumed by the handle when not supported by the hand of the user; and Fig. 4 is a transverse section taken on the line 4—4 of Fig. 2 in a plane at right angles to the section shown in Fig. 3; Fig. 5 is a sectional

view showing the scrap scraping position.

In the embodiment il-
concave disk 1 is show-
suitable material, pre-
nickel plated, the edge
on its outer face as sho-
sharp cutting edge for
surface to be cleaned.
is provided with a plur-
any desired number of
ployed, and which are d-
suction under the dis-
moved over the surface
thereby to facilitate i-
disk as here shown, is i-
trally disposed strap
mediately of its ends wi-
5 desired to form a po-
for supporting the han-
as shown, is made into
segmental openings 6 be-
site sides thereof with tl
of said openings dispose
of the strap.

A strap 7 similar to
ranged on the inner fa-
the strap 4 and is here s-
in width to said strap 4
termmediately of its leng-
loop 8 extending trans-
and arranged to regis-
the strap 4, thus formi-
9 substantially one han-
below the inner face of
signed for the recepti-
loop 11 extending trans-
end of the handle 10
handle 10 is pivotally
disk 1. As shown, this
its opposite ends to tl
disk 1 by soldering, or
any other suitable man-

The handle 10, as sho-
metal rod bent interme-
form a hand gripping 1
members 13 and 14 th-
ward each other and
point about midway th-
are shown united throu-
of their length by sole-
ited in any other
manner. The free ends
to form an elongated
end of the handle 10,

transversely of said handle and is mounted in the bearing 9 formed in the straps 4 and 7. As shown, the free ends of the rods or arms 13 and 14 are united intermediately of the outer member of the loop 11, being here shown connected by a sleeve 15 which may be soldered or connected thereto in any suitable manner and which reinforces these ends and forms a wear plate or sleeve at the connection of the handle with the disk. It will thus be seen that owing to the fact that the terminals of the members forming the handle are fixedly connected by the sleeve 15, it is necessary in order to insert the journal formed by these connected ends in the bearing 9 that the strap 7 be constructed in the form of a separate member to permit the mounting of the transverse handle loop in said bearing, it being of course understood that the ends are first inserted through the loop 5 of the strap 4 and the sleeve 15 then engaged with the ends and soldered or otherwise connected thereto and that the strap 7 is then placed in position and the opposed ends thereof secured to the inner face of the disk by soldering or otherwise. When so connected, the handle and disk will be inseparable, forming substantially a unitary structure, and all danger of the handle being accidentally disconnected from the disk is thereby avoided.

The ends of the loop 11 extend over the openings 6 at the opposite sides of the strap 4 and the inner wall of said loop is designed to engage the outer face of the disk 1 which is here shown as one end of the strap 4 when the handle is partially lowered, thereby holding said handle at an angle relatively to the disk and preventing it from falling flat against the disk. When so positioned, the ends of this loop 11 also bear against the outer curved edges of the openings 6 at one end thereof, which assists in supporting the handle in its angular position to facilitate grasping thereof by the user and whereby said disk is substantially rigidly connected with the handle during its movement sideways in either direction or rearward so that it may be tilted during the cleaning operation and either side edge or its rear edge caused to engage the surface over which it is being scraped for releasing stubborn sub-

stances which adhere to said surface. From the above description, it will be obvious that this disk may freely and quickly be passed over the surface to be cleaned with its cutting edges in engagement therewith, the openings 3 therein tending to break the suction and prevent binding of the disk on the surface over which it is being moved.

I claim as my invention:

A scraping device comprising a convexo concave disk having a central opening with a strap extending thereacross and having an outwardly bowed loop therein to form one member of a handle bearing, a strap arranged on the inner face of said disk below said first mentioned strap in alinement therewith and secured at its opposite ends to the inner face of the disk and having an inwardly bowed loop registering with the loop in the first-mentioned strap to complete the handle bearing, a handle composed of a metal rod bent intermediately of its ends to form a hand gripping loop and with the side members thereof converging toward each other and contacting from a point near the mid-length thereof toward their free ends and united throughout their contacting portions, the free ends of said rod being bent to form an elongated transversely extending loop, a sleeve connecting the terminals of said bent ends, and fixedly connected thereto forming a combined reinforce and wear plate, the outer side member of said transversely arranged loop being engaged with the bearing formed by said straps with the connecting wearing sleeve arranged in said bearing, the inner wall or side member of said transverse loop being spaced a sufficient distance only from the outer side member to permit the free turning of the outer side member in the bearing, whereby said inner member is adapted to engage the outer face of the disk on the lowering of the handle and thereby hold said handle at an angle in relation to the disk.

In testimony whereof I have hereunto set my hand in presence of two subscribing witnesses.

INA D. KINNE.
